UNITED STATES PATENT OFFICE

NIELS CHRISTIANSEN, OF HILTON VILLAGE, VIRGINIA

DOOR HOLDER

Application filed March 5, 1928. Serial No. 259,211.

This invention relates to builders' hardware and more particularly to a door holder by means of which a door may be securely fastened when shut or retained in a partially opened position.

One object of the invention is to provide a device of this character including a post carried by the door and a latching bar adapted to be connected with a door frame and movable into and out of position to engage the post.

Another object of the invention is to yieldably resist movement of the post and latching bar relative to each other when the post is engaged with the latching bar and thus prevent a rattling noise.

Another object of the invention is to allow the post to be slidably engaged with the latching bar or releasably engaged by a hook at the free end of the latching bar.

The invention is illustrated in the accompanying drawings, wherein—

Figure 1 is a perspective view showing the door closed and the latching bar secured out of position to engage the post carried by the door;

Fig. 2 is a perspective view showing the latching bar engaged with the post and disposed to prevent opening of the door;

Fig. 3 is a perspective view showing the latching bar engaged with the post and in position to retain the door partially opened, and

Fig. 4 is a top plan view showing a door retained in a partially opened position by a latching bar of a modified construction.

The door holder constituting the subject-matter of this invention is employed to retain a door 1 in either a closed or a partially opened position and includes a latching bar 2 which is formed of strong metal and may be of any desired length. This bar has one end formed with an opening 3 to receive a staple or eye 4, and by an inspection of Figs. 1, 2 and 3 it will be seen that the latching bar may be disposed in either a depending position or a substantially horizontal position and when in the depending position may be moved either into or out of position to secure the door. The eye 4 is carried by a plate 5 which

is secured to the door frame 6 by screws or other suitable fasteners 7 and is formed with marginal flanges so that a cushion 8 which is formed of rubber and projects through an opening 9 in the plate may be retained in position by an enlarged base disposed between the plate 5 and the surface of the door frame against which the plate is secured. A longitudinally extending slot 10 is formed in the latching bar and recesses 11 which are spaced from each other longitudinally of the bar lead from one side edge of the slot. Adjacent the attached end of the bar the slot 10 terminates in a curved extension 12 and at the junction of the slot with the side extension is formed a recess 13 which is of greater dimensions than the recesses 11 and also of greater dimensions than the width of the slot or its extension. A hook 14 is provided at the free end of the latching bar and at its attached end the latching bar is provided with a finger 15 which projects therefrom in alignment with the rear end of the side extension 12 of the slot. In order to prevent the latch bar from swinging toward and away from the door frame when in the inoperative position shown in Fig. 1, there has been provided a keeper 16 including a base or block 17 secured against the door frame and a latching strip 18 which is pivoted to the block or base 80 and of such length that, when turned from the position shown in Fig. 2 to that shown in Fig. 1, it can straddle the slot 10 and prevent the latching bar from swinging away from the door frame. The block is of such width that it may be snugly received in the slot and of such depth that its outer face will be substantially flush with the outer face of the latch bar. Therefore, when the latching strip is turned to the operative position, it 90 will bear against the latching bar at opposite sides of the slot and securely hold the latching bar against movement. Therefore, if the device is applied to the door of a state room upon a boat or train, movement of the boat or train will not cause the latching bar to swing toward and away from the door frame with resulting noise and marring of the door frame.

The post 19 which is carried by the door 100

and cooperates with the latching bar is also formed of metal and is provided with a base 20 having openings formed therein to receive securing screws 21. This post may be either 5 long or short according to whether the door opens inwardly or outwardly and adjacent its free end it carries a pin which projects transversely from the post and terminates in a head 22. The head is of such size that it 10 may be passed through the recess 13 to dispose the pin within the slot of the latching bar but is of sufficient diameter to prevent it from passing through the recesses 11 or through the slot at any point except the intersection of the slot with the extension 12 where the recess 13 is located. It will thus be seen that, when the pin is passed through the recess 13 and into the slot, the post and the latching bar will be connected and cannot 15 accidentally separate.

When the improved door holder is in use, the base plate 5 of the mounting is secured against the door frame adjacent the upper end of the door opening at one side thereof 20 and the post is secured to the door adjacent its top and close to the free side edge of the door. When the latching bar is secured to the door frame, as shown in Fig. 1, the door may be freely opened and closed. By releasing the 25 latch strip 17 and swinging the latching bar into position to permit the pin to be passed through the recess 13 and into the slot 10, the latching bar may be swung downwardly, as shown in Fig. 2, to dispose the pin at the 30 upper end of the curved extension 12. When so disposed, the latching bar will serve very effectively to prevent the door from being opened. Instead of moving the latching bar into position to dispose the pin in the side 35 extension 12, it may be supported in a substantially horizontal position after the pin has been moved into the slot and the door can then be opened as far as desired and the pin disposed in a selected recess or seat 40 11. When this is done, the door will be retained in a partially opened position, as shown in Fig. 3, and it cannot be entirely opened. If a person should attempt to enter a room having the door retained in a partially 45 opened position, this will be prevented as the pin cannot move out of the slot except through the recess 13 and the door must be closed before this can be accomplished. It will thus be seen that an unauthorized person 50 cannot release the latching bar from the pin by standing outside the room and then open the door a sufficient distance to enter. When the latching bar is in the horizontal position shown in Fig. 3, the finger extension 15 bears 55 against the cushion 8 and the cushion will be subjected to sufficient pressure to cause it to have a tendency to press upon the finger and thereby cause the pin to be yieldably retained in the seat 11 in which it is disposed. This 60 65 not only prevents the pin from accidentally

slipping out of the desired recess and permitting the door to move open beyond a desired extent but also prevents rattling noises which would be caused if the pin fitted loosely in the recesses. When it is desired to only temporarily retain the door partially opened, the 70 pin is engaged by the hook 14. When this is done, the door may be securely retained in a partially opened position but the latching bar can be very easily detached from the pin and return to the inoperative position 75 without its being necessary to first close the door in order to move the pin longitudinally through the slot and pass the pin outwardly through the recess 13.

The latching bar, which is shown in Fig. 4 and indicated by the numeral 23, is quite similar to the latching bar shown in Figs. 1, 2 and 3, but instead of being straight throughout its lengths it is curved longitudinally. This form of latching bar is intended to be disposed above the door instead of to one side of it. When this form of bar is employed, the base plate of the mounting 24 corresponds to the base plate 5 is secured in a horizontal position above the door opening in the door frame and the post 26 is secured to the door in such a position that its pin 27 will project vertically from the post above the plane of the upper edge of 80 the door. Therefore, the latching bar may extend horizontally above the door.

Having thus described the invention, I claim:

1. A door holder comprising a mounting 100 including an attaching plate adapted to be secured adjacent a door opening, an eye projecting outwardly from said attaching plate, a cushion of yieldable material projecting forwardly from said attaching plate in 105 spaced relation to said eye, a latch bar loosely engaged with said eye and formed with a longitudinally extending slot having side notches, the inner end of said bar being adapted to bear against said cushion when 110 the arm is extended away from the mounting, a post adapted to be secured to a door, and a pin projecting from said post and adapted to be slidably received in said slot and provided with a head to releasably retain the 115 pin in the slot.

2. A door holder comprising a mounting 120 adapted to be secured adjacent a door opening and including an eye, a cushion carried by said mounting in spaced relation to said eye, a latch bar loosely engaged with said eye and having its attached end provided with a finger to bear against said cushion when the bar is in an extended position, said bar being formed with a longitudinally extending track having seats leading therefrom and spaced from each other longitudinally of the track, and a post adapted to be secured to a door and provided with a pin slidably received in said track and engageable in 125 130

the seats to releasably retain the door in a set position.

3. A door holder comprising a mounting adapted to be secured adjacent a door opening and including an eye, a latch bar loosely engaged with said eye its free end provided with a hook, said bar having a longitudinally extending track formed with seats leading transversely therefrom, and a post adapted to be secured to a door and provided with a pin extension adapted to be engaged by said hook and slidably received in said track for movement from one seat to another whereby the door may be releasably secured in adjusted positions.

10 15 In testimony whereof I affix my signature.
